UNITED STATES PATENT OFFICE.

WILLIAM D. COOLIDGE, OF SCHENECTADY, NEW YORK, ASSIGNOR TO GENERAL ELECTRIC COMPANY, A CORPORATION OF NEW YORK.

REGULATOR FOR ELECTRICAL DISCHARGES.

Application filed January 30, 1923. Serial No. 615,953.

The present invention relates to regulation of the current in electric apparatus, and in particular to the regulation of current value in incandescent cathode vacuum tubes.

5 My invention is particularly applicable to the operation of thermionic devices by current derived from ordinary power circuits which are subject to considerable voltage fluctuation, altho its benefits are not confined 10 to such operation.

In accordance with my invention the current in an X-ray tube, or other electrical discharge device, is regulated by the intermediary of a second electrical discharge device 15 which is responsive to a magnified degree to current variations to be regulated and which controls the current-carrying capacity of the device to be regulated so as to maintain a substantially predetermined 20 current value. A substantially constant current may be maintained in accordance with my invention without moving parts or other complications and with a small expenditure of energy.

25 In the accompanying drawings, Fig. 1 illustrates an X-ray system adapted for operation with substantially constant current from a source of variable voltage; Fig. 2 illustrates a similar constant current system with some modification of connections; Fig. 3 illustrates a more highly developed system; and Fig. 4 illustrates a system containing a modified transformer arrangement.

The X-ray device 2 of Fig. 1 operates substantially by pure electron conduction, as described in my prior Patent 1,203,495 of October 31, 1916, and contains a cathode 3 and an anode 4 connected by the conductors 5, 6 to the secondary winding of a transformer 7. The primary of this transformer is connected by the conductors 8, 9 to current distribution lines 10, 11. The cathode 3 comprises in addition to the cylindrical member shown in the drawing, a heated filamentary member (not shown) which is supplied with heating current by the conductors 12, 13 connected to the secondary of a transformer 14 in series with a regulable resistance 15. The cathode of the X-ray tube is operated at saturation current, that is, the impressed

voltage is high enough to utilize substantially all of the available electrons emitted by the cathode.

A second electron discharge device 17 is provided also comprising an incandescent 55 cathode 18 and an anode 19 contained within an exhausted envelope. The temperature of the cathode 18 varies with variations of current in the circuit of the X-ray tube, for example, by being connected as shown to the primary of a step-down transformer 20, the primary of which is connected in series with the secondary of the transformer 7 by the conductors 21, 22. In Fig. 1 these conductors 21, 22 are connected into the center of the 60 secondary winding but if taps to this part of the transformer are not readily available, a connection as shown in Fig. 2 may be used in which the primary winding of the filament heating transformer 20 is connected in cir- 65 70 75 80 85 90 95 100

95 In the system shown in Fig. 1 the electrodes 18, 19 are supplied with operating current by connection to the secondary of a transformer 23, the primary of which derives current from the mains 10, 11, through the conductors 24, 25 in series with an impedance device 26. In Fig. 1 the conductors 24, 25 are connected directly to the mains 10, 11, whereas in Fig. 2 these conductors are connected to the cathode conductors 12, 13. In this case the transformer 20 and connected parts are at cathode potential and therefore, are insulated from lines 10, 11 by the transformer 14.

The temperature of the cathode 18 of the device 17 is so adjusted with respect to the impressed plate voltage furnished by transformer 23 that a saturation current is obtained. In other words, the applied voltage and the cathode temperature are so chosen that substantially all of the available electrons from the cathode are carried to the anode. This adjustment of cathode temperature can be carried out by properly propor-

tioning the voltage of the secondary of the transformer 20 to the resistance of the cathode 18.

When the current in the X-ray tube circuit rises above or falls below the predetermined value, the corresponding change of heating current in the filament 18 produces a magnified change of space current to the anode 19. At saturation, the current from an incandescent cathode varies in accordance with Richardson's equation.

$$I = a \sqrt{T} e^{-\frac{b}{T}}$$

(I is current value; T absolute temperature of the cathode, a and b are constants and e is the base of natural system of logarithms.)

As expressed by this equation the electron current varies at a rapid rate with the temperature, and hence at a rapid rate with the heating current. A 10% increase of heating current may increase the space current through the tube as much as 300%.

This rapid variation of current withdrawn from the lines 10, 11 produces an accompanying large change in voltage drop in an impedance device 26, which may be constituted by an iron wire ballast in hydrogen or by a reactance. The impedance or voltage-consuming device 26 is connected in series relation to the regulator tube 17 through the intermediary of the transformer 23. Current drawn by the tube 17 varies the voltage drop in the impedance 26, and hence modified the voltage of the heating circuit 12, 13 through the intermediary of the transformer 14. A decrease of voltage at the terminals of the primary of the transformer 14 reduces the voltage of the cathode heating current and hence reduces the cathode temperature of the device 2. By a converse process an incipient fall of current through the X-ray tube decreases the current carrying capacity of the vacuum tube 17, hence decreases the current in the impedance 26, decreases the voltage drop and increases the temperature of the cathode in the X-ray tube. As either a rise or fall of current is immediately counteracted by a change in cathode temperature of the X-ray tube, the current cannot depart to an appreciable extent from a predetermined value.

The system shown in Fig. 3 has certain advantages when wide fluctuations of voltage of the supply current occurs. For example, but a single adjustment is required to get regulation over a wide range of X-ray tube load. In this system I have provided a second electron regulator 30 having a main or plate circuit 31, 32 connected across the secondary of the transformer 23 in parallel with the device 17. The cathode heating circuit 33, 34 of this second tube derives current through a transformer 35 from the

mains 10, 11 in series with an impedance 36. A rise of voltage in the mains 10, 11 raises the voltage of the heating current of the cathode in the device 30, thereby producing in an amplified degree an increase of space current which being drawn from the mains 10, 11 will increase the voltage drop in the impedances 36, 37, and thereby lower the voltage of the current drawn by the transformer 14 for heating the cathode of the X-ray tube 2. The size of the impedance 36 is chosen with respect to the variations of voltage in the heating current for the cathode of the device 30 to vary the temperature and hence the electron (or space) current sufficiently to produce such added potential drop that the potential at the terminals of the conductors 38, 39 would be substantially constant, if there were no variations of current in the device 17 caused by internal changes in the X-ray tube.

When internal changes in the X-ray tube 2 occur, caused for example, by some evolution of gas from the anode, or other metal part, or by the aging of the cathode during use, or any other reason, then the consequent change in space current through the X-ray tube will vary the current-carrying capacity of the device 17, thereby producing the proper corrective change in cathode temperature to restore the current to substantially the original desired value. A resistance 40 may be provided to determine the current through the X-ray tube. By adjusting this variable resistance device 40 the load current of the X-ray tube may be set at a desired value and the regulator will maintain this current value substantially constant in spite of internal changes in the vacuum tube or voltage changes in the supply line.

As the space current through a device such as an X-ray tube is relatively small and the voltage is very high a high ratio of primary to secondary turns in the transformer 20 is required to step this high voltage energy, of small current value to a low voltage current of greater amperage suitable for filament heating purposes. To reduce the number of primary turns a separate primary winding may be provided to furnish the greater part of the heating current, the variable current component being furnished by another primary winding receiving current proportional to space current in the device being regulated.

In Fig. 4 the filament of the regulating electron discharge device is supplied with current from a secondary winding 41 of the transformer 42. The core 48 of this transformer has an air-gap as indicated. A primary winding 43 receives current from the lines 10, 11 by the conductors 49, 50 in series with a regulating resistance 44. A second primary winding 45 is provided for receiving current by the conductors 46, 47 in cir-

cuit with the secondary winding of the main transformer 7 and hence also with the X-ray tube 2.

In a co-pending application, Serial No. 5 615,952, filed concurrently herewith, I have made generic claims on the regulation of line conditions by an electron discharge used in conjunction with a voltage consuming device.

10. What I claim as new and desire to secure by Letters Patent of the United States, is:

1. The method of controlling the current value of an electron discharge which consists in producing an independent electron discharge, varying the current-carrying capacity of said second discharge in accordance with the variations of current to be regulated, producing a substantial drop of voltage by said second discharge proportional 15 to the current value thereof, and varying the electron-generation at the cathode of said first discharge inversely with said voltage drop.

2. The method of regulating a varying 25 electrical condition in a circuit which consists in producing independently an electron discharge at saturation current, varying the electron emissivity of the cathode of said discharge in accordance with variations of the condition to be regulated, producing a drop 30 of voltage by said discharge proportional to the current value thereof, and regulating said varying condition inversely with voltage variations in said second circuit.

3. The method of regulating the space or 35 electron current in a vacuum tube having an incandescent cathode supplied with current of variable potential, which consists in adjusting the temperature of the cathode of said tube with respect to the applied voltage 40 to produce saturation current, producing a second electron discharge, varying the second discharge in response to the variations of space current of the first discharge, and controlling the temperature of the cathode 45 in the tube being regulated inversely as a function of current variations of the second discharge.

4. The method of regulating the current 50 in an X-ray device which consists in producing an electron discharge at saturation current in an independent circuit, varying the generation of electrons supporting said discharge in accordance with current variations in said X-ray device, producing a drop 55 of voltage by said discharge, and regulating the current in the X-ray device in accordance with voltage variations in said second circuit.

5. The method of operating an X-ray tube 60 having an incandescent cathode supplied with current of variable voltage which consists in producing a second electrical discharge, varying the current value of said second discharge directly in response to

variations of current in said X-ray tube, producing a voltage drop externally to said second discharge, varying in accordance with the current of said discharge, and controlling the temperature of said X-ray cathode 70 in accordance with the difference between the variable voltage of the cathode heating circuit and the voltage drop produced by said second discharge.

6. The method of regulating the space 75 current in an electron discharge device containing an incandescent cathode and an anode which consists in heating said cathode at incandescence, conducting an electron current between said electrodes at a voltage materially above the voltage necessary to produce a saturation current, producing a second electron discharge at the saturation current value, varying the emission of said second discharge in response to the variation of the current of the first discharge, and varying the emission of the first discharge inversely with respect to the current of the second discharge.

7. An electric system of distribution comprising a circuit one of the electrical conditions of which is subject to variation, a second circuit, an electron discharge device in said second circuit, means for varying the current-carrying capacity of the device in said second circuit in accordance with the varying condition to be regulated, means for producing a substantial drop of voltage varying with the current output of said discharge device, and means for regulating the electrical condition subject to variation inversely with said voltage drop.

8. An X-ray system comprising an X-ray tube, a source of current connected thereto, a second circuit, a thermionic device operated at saturation by current derived from said second circuit, means for varying the electron emission of said device in accordance with variations of current in said X-ray tube, means for producing by said device a drop of voltage, and means for varying the current carrying capacity of said X-ray tube in response to the difference between the voltage in said second circuit and said drop of voltage.

9. An X-ray system comprising an electric distributing circuit, an X-ray tube, transformer means for supplying said tube from said circuit, a voltage-consuming means also supplied from said circuit, a thermionic device connected to derive current through said means, means for varying the current-carrying capacity of said device in response to the current value in said X-ray tube, a second thermionic device, means for varying the current carrying capacity of said second device in response to the differences between the voltage of said distributing circuit and the voltage drop in said consuming means, a second voltage consuming

- device traversed by current supplied to both said thermionic devices, and means for heating the cathode of said X-ray tube by current having a voltage proportional to the differences between the voltage of said distributing circuit and the combined voltage drop in said voltage consuming means. 5
10. An electric system of distribution comprising a circuit carrying current one of the varying electric conditions of which is to be regulated, a second circuit, a thermionic discharge device fed by said second circuit, said device containing a cathode operated at saturation current, and means for varying the electron emission of said cathode in accordance with the varying condition of the first circuit which is to be regulated, means for producing a drop of voltage varying with the current traversing said discharge device, and means for regulating the varying electric condition of said first circuit in response to the voltage of said second circuit as modified by said voltage drop. 15
20. 11. The combination of two electron conduction devices, a space current circuit and an electrode heating circuit for each of said respective devices, means for varying the current in one of said heating circuits directly in response to the current in the space circuit of the other device, and means for varying the heating current of the other electron device inversely with the current in the space circuit of the first device. 25
30. 12. An electric system comprising a source of electric energy, a vacuum tube having electrodes at least one of which is adapted to emit electrons when heated, circuit connections for supplying said electron emitting cathode with heating current from said source, a main operating circuit for supplying said tube with space current from said source, a second vacuum tube containing electrodes one of which is adapted to be heated, means for supplying a saturation current to said tube from said source, means for varying the electron emission in said second tube in response to space current variations of the first tube, and means connected to the electrodes of the second tube for varying the heating current of said first tube inversely with the electron emission in the second tube. 35
40. 13. The combination of a thermionic discharge device, a second thermionic discharge device, means for varying the current carrying capacity of said second thermionic device in response to variations of current value in said first thermionic device and means for regulating the temperature of a thermionic electrode in said first device through the intermediary of current variations in said second device. 45
50. 14. In combination with a thermionic X-ray tube, a thermionic regulator tube, means for varying the current carrying capacity of said regulator tube in response to current variations in said X-ray tube, and means for regulating the temperature of the cathode of said X-ray tube in response to current variations of said regulator tube. 55
60. 15. Electrical discharge apparatus comprising an electron discharge device having an incandescent cathode, a main supply circuit therefor, a second electron discharge device having an incandescent cathode, means for heating the cathode of the second discharge device by current varying directly with current in said main supply circuit, a second supply circuit for said second discharge device, an impedance device in said second circuit, and means for heating the cathode of the first discharge device by current having a voltage proportional to the difference between the voltage of said second supply circuit and the voltage drop in said impedance. 70
65. 16. The combination of a thermionic device, a second thermionic device, means whereby the electron current in the second device is varied directly with the current in the first device, and means for varying the electron current in said first mentioned electron device inversely with the current traversing the second device. 75
70. 17. An X-ray apparatus comprising the combination of an X-ray tube having a cathode adapted to emit electrons when heated by passage of current, a supply circuit connected to the electrodes of said tube, a regulator vacuum tube having an electron-emitting cathode adapted to be heated by passage of current, connections for heating said cathode with current which is proportional to the main load current of the X-ray tube, a supply circuit for said regulator tube, a voltage-consuming device in said supply circuit connected to modify the voltage of said circuit in response to current supplied to the regulator tube, and means for heating the X-ray tube cathode by current having a voltage proportional to the modified voltage of said supply circuit. 80
75. 18. The combination of a main thermionic discharge device in which a constant current carrying capacity is desired, a regulating thermionic device, a supply circuit for said regulating device, means for varying the current-carrying capacity of said regulating device in response to incipient variations of current in said first device, means for producing in said supply circuit a drop of voltage proportional to a current traversing said second device, a second regulating thermionic device, means for varying the current-carrying capacity of the second regulating device in response to voltage variations in the supply circuit of the first regulating device, means for producing an added potential drop in said supply circuit pro- 85
80. 19. In combination with a thermionic X-ray tube, a thermionic regulator tube, means for varying the current carrying capacity of said regulator tube in response to current variations in said X-ray tube, and means for regulating the temperature of the cathode of said X-ray tube in response to current variations of said regulator tube. 90
85. 20. 21. The combination of a thermionic device, a second thermionic device, means whereby the electron current in the second device is varied directly with the current in the first device, and means for varying the electron current in said first mentioned electron device inversely with the current traversing the second device. 95
90. 22. An X-ray apparatus comprising the combination of an X-ray tube having a cathode adapted to emit electrons when heated by passage of current, a supply circuit connected to the electrodes of said tube, a regulator vacuum tube having an electron-emitting cathode adapted to be heated by passage of current, connections for heating said cathode with current which is proportional to the main load current of the X-ray tube, a supply circuit for said regulator tube, a voltage-consuming device in said supply circuit connected to modify the voltage of said circuit in response to current supplied to the regulator tube, and means for heating the X-ray tube cathode by current having a voltage proportional to the modified voltage of said supply circuit. 100
95. 23. The combination of a main thermionic discharge device in which a constant current carrying capacity is desired, a regulating thermionic device, a supply circuit for said regulating device, means for varying the current-carrying capacity of said regulating device in response to incipient variations of current in said first device, means for producing in said supply circuit a drop of voltage proportional to a current traversing said second device, a second regulating thermionic device, means for varying the current-carrying capacity of the second regulating device in response to voltage variations in the supply circuit of the first regulating device, means for producing an added potential drop in said supply circuit pro- 105
100. 24. In combination with a thermionic X-ray tube, a thermionic regulator tube, means for varying the current carrying capacity of said regulator tube in response to current variations in said X-ray tube, and means for regulating the temperature of the cathode of said X-ray tube in response to current variations of said regulator tube. 110
105. 25. The combination of a main thermionic discharge device in which a constant current carrying capacity is desired, a regulating thermionic device, a supply circuit for said regulating device, means for varying the current-carrying capacity of said regulating device in response to incipient variations of current in said first device, means for producing in said supply circuit a drop of voltage proportional to a current traversing said second device, a second regulating thermionic device, means for varying the current-carrying capacity of the second regulating device in response to voltage variations in the supply circuit of the first regulating device, means for producing an added potential drop in said supply circuit pro- 115
110. 26. In combination with a thermionic X-ray tube, a thermionic regulator tube, means for varying the current carrying capacity of said regulator tube in response to current variations in said X-ray tube, and means for regulating the temperature of the cathode of said X-ray tube in response to current variations of said regulator tube. 120
115. 27. The combination of a main thermionic discharge device in which a constant current carrying capacity is desired, a regulating thermionic device, a supply circuit for said regulating device, means for varying the current-carrying capacity of said regulating device in response to incipient variations of current in said first device, means for producing in said supply circuit a drop of voltage proportional to a current traversing said second device, a second regulating thermionic device, means for varying the current-carrying capacity of the second regulating device in response to voltage variations in the supply circuit of the first regulating device, means for producing an added potential drop in said supply circuit pro- 125
120. 28. In combination with a thermionic X-ray tube, a thermionic regulator tube, means for varying the current carrying capacity of said regulator tube in response to current variations in said X-ray tube, and means for regulating the temperature of the cathode of said X-ray tube in response to current variations of said regulator tube. 130

tional to current traversing the second regulating device and means for heating the cathode of the main discharge device of current having a voltage proportional to the modified voltage of said supply circuit.

19. The method of regulating the current in a thermionic discharge which consists in producing a second thermionic discharge, varying the current-carrying capacity of

said second discharge in response to current variations in the discharge to be regulated and controlling the generation of electrons for supporting said first discharge through the intermediary of said second discharge.

In witness whereof, I have hereunto set my hand this 29th day of January, 1923.

WILLIAM D. COOLIDGE.
